Del., a corporation of Delaware

Application July 8, 1947, Serial No. 759,666

15 Claims. (Cl. 60—97)

1

This invention relates to presses, and particularly to multi-point presses wherein there are a plurality of points at which power is applied to the press platen for moving it.

The particular object of the present invention is to provide an improved arrangement for maintaining a multi-point press platen level.

Still another object of this invention is to provide a means for maintaining the platen of a multi-point press level and which utilizes a minimum of auxiliary equipment in accomplishing this result.

Still another object of this invention is the provision of a mechanism for maintaining a multi-point press platen level which is substantially instantaneous in operation.

Still another object is to provide a means for maintaining a press platen level which may readily be installed on the platen of any press.

It is also an object of this invention to provide in combination with a hydraulic press having a plurality of spaced rams acting on a platen, a means for controlling the delivery of fluid to the said rams whereby the said platen remains level at all times.

These and other objects and advantages will become more apparent upon reference to the following description taken in connection with the accompanying drawings in which:

Figure 1 is a diagrammatic view of a two-point hydraulic press having a platen leveling mechanism according to this invention;

Figure 2 is a fragmentary view as showing a somewhat modified construction to be utilized in connection with the arrangement of Figure 1;

Figure 3 is a view similar to Figure 1 but showing a somewhat different arrangement wherein separate pumps are employed for supplying fluid to the platen actuating rams;

Figure 4 is a detailed view showing one part of the pump control linkage of Figure 3;

Figure 5 is a diagram of the electrical control circuit for the arrangement of Figure 3;

Figure 6 is a view showing still another form of this invention and wherein the control of the platen is accomplished through pressure;

Figure 7 is a perspective view showing how this invention can be applied to a press having four rams connected with the platen;

Figure 8 is a diagrammatic view showing this invention applied to a long platen having a plurality of rams spaced therealong; and

Figure 9 is a perspective view showing a simplified form of this invention.

2

General arrangement

According to this invention the platen of a press having a plurality of actuating means for the platen is maintained level by means of a flexible member such as a cable which is connected between the press head and press bed and which passes across the press platen. The flexible member is anchored on one of the head or bed and there are pulleys or other journaling means on the platen and the other of said head or bed whereby tilting movement of the platen will produce relative movement between the flexible member and the one of said head or bed on which it is journaled. This relative movement may be resisted by heavy yielding means which normally support the weight of the platen or may be employed for actuating hydraulic or electrical means which control the delivery to the actuating means for the press platen to set up forces therein which will restore the platen to its level condition.

Preferably, the actuating means for the press platen are hydraulic motors such as rams and the means for maintaining the platen level, and which are under the control of the flexible member, comprise flow dividing valves, pressure control valves, or delivery control means for pumps supplying the said rams.

Structural arrangement

Referring to the drawings, the press shown in Figure 1 comprises a bed 10 and a head 12 which is connected with the said bed by the strain rods 14. A platen 16 is slidable on strain rods 14 between the head 12 and bed 10. The platen is actuated by a pair of rams 18 which extend into the cylinder 20 which are preferably integral with the head 12.

40 A pump 22 is connected by a conduit 24 with the retracting means of the rams 18 and, by a conduit 26 with the inlet of a flow dividing valve 28. The flow dividing valve 28 has two service ports which are connected by the conduits 30 with the advancing means of the rams 18. The valve 28 also has therein a valve member 32 which in its center position offers equal restriction to the fluid flow from the conduit 26 to each of the conduits 30. Upon movements in either direction the valve member 32 decreases the restriction to flow to one of the conduits 30 while increasing the restriction to flow to the other conduit 30.

55 For pre-filling the advancing means for the rams during their initial downward movement,

and for exhausting the said advancing means during the retracting movement of the rams, there are preferably provided surge valves 34 which connect the said advancing means with the reservoir 36 in response to suction in the advancing means or in response to a predetermined pressure acting in the retracting means of the rams. A check valve 38 opens from the reservoir 36 into the conduit 24 for supplying makeup fluid to the pump 22 during the working stroke of the rams 18.

Control of the pump delivery is had by a linkage 40 which includes the vertical rod 42 that passes through an arm 47 on the platen 16 and has as its upper end a solenoid armature arrangement 44. Energization of the solenoid 44 will lift the rod 42 and through the linkage 40 place the pump 22 in position to deliver into the conduit 26. De-energizing of the solenoid 44 permits the springs 46 to move the rod 42 downwardly and to place the pump in position to deliver to the conduit 24.

For actuating the valve member 32 of the flow dividing valve 28 there are provided a pair of flexible cables indicated at 48 and 50. The ends of these cables are anchored as at 52 and 54 to the bed 10 and pass upwardly therefrom to the pulleys 56 and 58 on the platen 16. The cables then pass across the platen in opposite directions to the pulleys 60 and 62. Then the cables extend upwardly and over the pulleys 64 and 66 carried by the press head. The ends of the cables are then fastened together by a suitable fitting 68. The anchors at 52 and 54 are preferably adjusted to hold the cable perfectly taut throughout its length.

The valve member 32 of the valve 28 is connected by the lever 70 which is pivoted at 72 with the member 68. A pin and slot arrangement at 74 interconnects the lever and member for simultaneous movements.

It will be apparent that, should the right end of the platen 16 tilt downwardly as viewed in Figure 1, the length of cable from the anchor 52 over the pulley 56, pulley 60, and extending upwardly to pulley 64, will become greater than the length of the cable extending from the anchor 54, the pulley 58, pulley 62 and up to pulley 66. Accordingly, there will be a movement toward the right of the horizontal reach of the cable extending between the pulleys 64 and 66 and also a movement to the right of the member 68 and the lower end of the lever 70. This brings about a movement to the left of the upper end of the member 70 and of the valve member 32 which operates to restrict the flow of fluid from the conduit 26 to the right hand conduit 30, and to reduce the restriction to flow from the conduit 26 to the left hand conduit 30. The pressure acting on the right hand ram 18 is therefore less than that acting on the left hand ram 18 and unbalanced forces are generated thereby which tend to restore the platen 16 to its level condition.

It will be apparent that either direction of tilting of the platen 16 from level will be followed by the setting up of unbalanced forces thereon tending to bring it back to its level condition.

The ends of the cables 48 and 50 may be adjusted at their anchors 52 and 54 respectively in order to pre-set the valve 28 to bring the rams 18 into synchronism under normal operating conditions.

In certain instances wherein the press platen

75

is not of too great a weight, it may be maintained level by mechanical means prior to the time it engages the work. This may be done by making the flexible cable sufficiently strong to support the weight of the platen and making the journals or pulleys on the platen in the head of sufficient size and strength also to support the weight of the platen. The connection of the cable to the flow dividing valve is then made as is shown in Figure 2. In this figure there is a block 76 which is secured to the cable ends and which carries a pin 78 extending into the bifurcated lower end of the lever 70. Rigidly mounted on the press head are a pair of stop members or abutments 80 of the same width as the block 76 and bearing against either side of the blocks 80 are the plates 82 which are apertured to permit the passage therethrough of the cable member.

Spaced from the plates 82 are the blocks 84 which are rigidly secured to the press head as by the screws 86 and between which and the blocks 82 there bear the heavy compression springs 88.

It will be apparent that the arrangement is that of a self-centering device and that the block 76 will normally be retained in its Figure 2 position and that movement thereof in either direction will be resisted by the full thrust of one of the springs 88. As mentioned before, this arrangement will operate to maintain the platen level up until the time it strikes the work, provided the cable and pulleys therefrom and the springs 88 are made sufficiently strong.

There is shown in Figure 3 a somewhat modified arrangement wherein each of the two rams for actuating the platen has its own individual pump.

The construction of the two rams and the actuating circuits therefor are identical and accordingly a description of only one thereof will be given and the one on the other side of the press will be correspondingly numbered with the addition of an A.

Referring to Figure 3, the actuating rams are indicated at 90 and 90A. Connected between the advancing and retracting means of the ram 90 is a pump 92 having a servomotor mechanism 94 shiftable for selectively reversing the pump delivery. A linkage 96 is connected to the servomotor 94 with a rod 98 which is arranged like the rod 42 in Figure 1 with an actuating solenoid 100. A link 102 is included in the linkage 96 and is operable, when extended, to move the pump 92 toward retraction stroke position. Thus, if the pump 92 is delivering to the advancing means of the ram 90 and the link 102 is extended, the delivery of the pump 92 will be reduced and the ram 90 will slow down.

The link 102 is best seen at Figure 4 wherein it comprises a casing 104 having therein a movable member 106 normally urged in one direction by a spring 108 and adapted for being moved in the other direction by energization of a solenoid 110. One end of the casing 104 is connected with the linkage 96 and the opposite end of the member 106 is also connected with the said linkage. It will be apparent that energization of the coil 108 will operate to increase the effective length of the link 102.

A simplified electrical control circuit for the arrangement of Figure 3 is shown in Figure 5. In this figure there are the power lines L-1 and L-2 and therebetween there is connected a contactor coil A in series with the normally opened start button 112 and the normally closed stop button 114. The start button 112 is by-passed

by the normally opened blades A-1 of the contactor coil A which provides a holding coil for the contactor coil after the latter has been energized by closing the push button 112.

Connected in parallel with coil A are the solenoids 100 and 100-A energizable for shifting their associated pumps 92 and 92-A into forward delivery position.

The coil 110 of the extensible link 102 is connected between the lines L-1 and L-2 and in series with a normally opened limit switch LS-1 while the coil 110-A of the extensible link 102-A is connected in series with the normally opened limit switch LS-2.

The limit switches are positioned as shown in Figure 3 on either side of a member 113 which is secured to the cable 115. As explained in connection with Figure 1 tilting movements of the platen 116 will be accompanied by movement in one direction or the other of the member 113 with the cable 115. For example, tilting of the platen 116 downwardly at its right end will result in a movement toward the left of the member 113 and closure of the limit switch LS-2. This will reduce the delivery of the pump 92-A and thereby slow down the rate of movement of the ram 90-A. This will operate to restore the platen to its level condition whereupon the limit switch LS-2 will again open and full delivery of the pump 92-A will be resumed.

In Figure 6 there is shown an arrangement somewhat similar to that shown in Figures 1 and 3 and wherein each of two rams has its own source of pressure fluid, but wherein the control of the tilting of the platen is accomplished by pressure responsive means.

Referring to only the left hand side of the arrangement shown in Figure 6, and applying the same numerals to the right hand side with the addition of an A, there is a ram 120 which has its advancing and retracting means connected with the service ports of a reversing valve 122. The valve 122 receives pressure fluid from a conduit 124 which leads to one port of a valve 126 which also has another port therein connected by the conduit 128 to receive pressure fluid from the pump 130. The valve 126 has therein a valve member 132 which is normally urged by the spring 134 into position to provide free communication between the conduits 124 and 128. Movement of the valve member 132 in the opposite direction will set up a restriction to flow between the said conduits.

The valve member 132 has thereon a fluid operable area connected by the conduit 136 with the conduit 124 and acting in a direction opposite to the thrust of the spring 134. The conduit 124 is also connected by a conduit 138 with the smaller side of a piston 140 which is connected with the movable flow control member of the pump 130 and acting in a direction to increase the delivery of the said pump. The pump is also urged toward increased delivery position by a spring 142 and the opposite side of the piston 140 is also connected by a conduit 144 with the conduit 128 for urging the pump toward decreased delivery position.

The spring 134 has its end opposite the valve member 132 engaged by a cup or washer 146 which is abutted by the end of a rod 148 adjustably carried in a fitting 150. The fitting 150 is connected for actuation by lever 152 which is pivoted at 154 and which has its lower end connected with the cable 156 for movements thereby.

In operation, a downward movement of the platen is brought about by shifting the valves 122 and 122-A to connect the conduits 124 and 124-A with the advancing sides of the rams 120 and 120-A. Equivalent conditions of fluid communication between the pumps 130 and 130-A through the valves 126 and 126-A with the said advancing means will obtain until the platen tilts from a level position. Upon any delivering movement of the platen 158 the lever 152 will be shifted about its pivot 154 to increase the tension on one of the springs of the valves 126 and 126-A and to decrease the tension on the other. Assuming that the platen has delivered downwardly on its right side as viewed in Figure 6, the tension on the spring 134 will be increased and that of the spring 134-A will be decreased. This will cause the valve member 132-A to yield under a lower pressure and thus to set up a restriction to flow from the conduit 128-A to the conduit 124-A. On the other hand, the valve member 132 will only yield at a higher pressure and therefore less restricted communication is had between the conduits 128 and 124. Normally, the valves 126 and 126-A will be adjusted whereby the valve members 132 and 132-A will float in a semi-restricting position and any tilting of the platen will be accompanied by an immediate increase in pressure on the lagging ram and a decrease in pressure on the leading ram.

In Figure 7, there is shown arrangement whereby a press platen having four actuating rams could be controlled according to this invention.

In Figure 7 a first cable 200 is connected to pass diagonally across or through the platen 202 and is connected with the control means 204 for the rams 206 positioned at the said diagonally opposite corners. The rams 208 on the other diagonally opposite corners are similarly controlled by a cable 210 which crosses the platen diagonally and in alignment with the said rams. By the arrangement shown in Figure 7 the platen is maintained substantially level because each corner of the platen is controlled by the one diagonally opposite. Thus, the platen cannot tilt in any direction without disturbing the balance of the control system for the several rams.

In Figure 8 there is shown an arrangement wherein there are a plurality of rams arranged in a line to actuate a platen such as a bending brake, a shear, or the like. In accordance with the principles set forth in connection with Figure 7, the two rams 212 are connected together through a flow dividing valve 214 which is controlled by the cable 216 which passes across or through the platen 218 between the rams 212. Similarly, the two rams 220 are connected together by the flow dividing valve 222 which is controlled by a cable 224 arranged relative to the ram 220 like the cable 216 is relative to the ram 212.

As in the case of the arrangement shown in Figure 7 the platen 218 is maintained level at all times and tilting or bending in any direction will result in immediately setting up restoring forces thereon.

Figure 9 shows a simplified arrangement wherein there is a single cable 300 which is anchored at 302 on the bed 304 and which extends upwardly and around the pulleys 306 and 308 on the platen 310. From the pulley 308 the cable 300 passes upwardly and around the pulley 312 on the press head 314. The end of the cable

300 is then anchored through a spring 316 which normally maintains the cable taut.

The two rams 318 of the press are connected through the flow dividing valve 320 which is secured to the valve 28 shown in Figure 1 and which is actuated by the lever 322 which is pivoted on the head 314 and connected with the cable 300.

The arrangement shown in Figure 9 is quite simple and is adequate in any instance wherein it is not desired to support the platen weight by the cable, or wherein it is not desired to provide for a pre-stressed cable as in the other modifications illustrated.

It will be understood that this invention is susceptible to modification in order to adapt it to different usages and conditions and, accordingly, it is desired to comprehend such modifications within this invention as may fall within the scope of the appended claims.

I claim:

1. In a press having a press head, a press bed, and a press platen reciprocable therebetween; a plurality of fluid operable means for reciprocating said platen; a fluid source for supplying pressure fluid to said means; flow controlling means for determining the relative amounts of fluid supplied to said means; a substantially inextensible and flexible member connected between said head and bed and extending transversely across said platen; and means connecting said member with said flow controlling means for operation thereof by deflections of said platen from a level position.

2. In a hydraulic press; end members constituting a press head and a press bed, and a press platen reciprocable therebetween; a plurality of fluid operable means for reciprocating said platen; means of supplying actuating fluid to said fluid operable means; flow controlling means operable for determining the relative quantities of fluid supplied to said fluid operable means; and means for actuating said flow controlling means in response to tilting movements of said platen comprising a flexible and substantially inextensible member anchored on one of said end members, extending therefrom to said platen, across said platen and thence to the other of said end members; and means connecting the end of said flexible member at said other end member to said flow controlling means.

3. In a press; end parts constituting a head and a bed, and a platen reciprocable therebetween; a plurality of fluid operable motor means connected with said platen for driving it in its reciprocating movements; a flexible cable extending transversely across said platen and from one end thereof toward one of said end parts and from the other end thereof toward the other of said end parts; means anchoring one end of said cable on one of said end parts; the other end of said cable being movable relative to the other end part; a fluid source for supplying fluid to said fluid operable means, flow dividing means between said source and said fluid operable means to determine the division of fluid therebetween; and means connecting the said other end of said flexible member with said flow dividing means.

4. In a hydraulic press having a head, a bed, and a platen reciprocable therebetween; a plurality of spaced fluid operable motors for driving said platen in its reciprocating movements; means for supplying actuating fluid to said motors; flow controlling means for determining the relative amounts of fluid to be supplied to said motors; and means of actuating said flow con-

trolling means in response to tilting movements of said platen comprising cable means anchored on said bed, extending to said platen, transversely across said platen, and thence to said head to be connected with said flow controlling means.

5. In combination with a press comprising rigidly interconnected end parts and a platen reciprocable therebetween, and having a plurality of fluid operable motors for actuating said platen; fluid flow controlling means for determining the supply of fluid to said motors and operable to vary the relative quantities supplied to the separate motors; and means of actuating said flow controlling means comprising cable means connected therewith, extending transversely across one of said end parts, then to opposite ends of said platen, then across said platen in opposite directions, and then to the other of said end parts and rigidly anchored thereon.

10 6. In a press having a head, a bed and a platen; cable means having its opposite ends anchored on said bed and extending therefrom to said platen, then across said platen in opposite directions, then to said head, and then across said head; means normally urging said cable toward a predetermined fixed position whereby said platen is normally maintained level; fluid motors acting on said platen at spaced points; control means for regulating the fluid supply to said motors; and means responsive to movements of said cable relative to said head brought about by the tilting of said platen for actuating said control means to regulate the fluid supply to said motors to set up unbalanced forces on said platen tending to restore the same to a level position.

25 7. In a press having a spaced apart head and bed and a platen reciprocable therebetween; cable means having its opposite ends anchored on said bed and extending therefrom to said platen in a direction parallel to the movement of said platen, across said platen in opposite directions, then to said head also in a direction parallel with the movement of said platen, and then across said head; centering springs on said head engaging said cable and normally urging it into a predetermined condition for normally maintaining said platen level; motor means acting on said platen at spaced points; control means for controlling the energization of said motor means; and means responsive to relative movements of said cable and head as brought about by tilting movements of said platen for actuating said control means to vary the energization of said motor means to set up unbalanced forces on said platen tending to return it to a level position.

40 8. In a press having a head and a bed spaced apart vertically and a platen reciprocable therebetween; cable means anchored at opposite ends of said bed and extending vertically therefrom to said platen, then across said platen in opposite directions, then vertically to said head, and then across said head; centering spring means continuously urging said cable into a predetermined position relative to said head; and fluid operable means responsive to relative movements between said head and cable for setting up unbalanced forces on said platen.

45 9. In a press having end members constituting a head and a bed and a press platen movable between said end members; a plurality of fluid operable motors connected with said platen for reciprocating the same; a pump connected with each said motor for supplying actuating fluid thereto; delivery controlling means for each of 50 said pumps operable for varying the delivery

thereof; and means for operating said delivery control means to vary the delivery of said pumps to said motors for maintaining said platen parallel to a predetermined plane at all times and comprising cable means extending transversely across said platen and then to said end members in a direction parallel with the direction of movement of said platen; means anchoring said cable means on one of said end members; and means connecting said cable means remote from the point of anchoring thereof with said delivery controlling means.

10. In a hydraulic press; a head, a bed and a platen; a plurality of fluid motors connected for actuating said platen; cable means anchored at opposite ends of said bed and extending therefrom to said platen in a direction parallel with the direction of movement of said platen; journal means at opposite ends of said platen, said cable means passing over said journal means, transversely across said platen, and toward said head in the same said direction; journal means at opposite sides of said head, said cable means passing over said journal means and extending transversely across said head; and means connected for operation by said cable means in response to movements thereof relative to said head for determining the relative quantities of fluid to be supplied to said motors.

11. In a hydraulic press; a press head, a press bed, and a press platen reciprocable between said head and bed; spaced fluid operable motors for actuating said platen; pressure fluid supply means for supplying actuating fluid to said motors; flow controlling means operable to determine the relative quantities of fluid to be supplied to said motors; yielding means continuously urging said flow controlling means toward one extreme position; and cable means also connected with said flow controlling means for the operation thereof upon deflections of said platen from a level position, said cable means extending therefrom to said platen; then across said platen to the opposite end thereof, and then to said bed to be anchored thereon.

12. In a press having end parts constituting a head and a bed, a platen reciprocable therebetween, a plurality of spaced fluid motors for actuating said platen, and fluid supply means for supplying actuating fluid to said motors; platen leveling means comprising flexible inextensible means extending from one side of one of said end parts to the other side of the other of said end parts and passing transversely across said platen; journal means at opposite sides of said platen for supporting said flexible means; means rigidly anchoring said flexible means on one of said end parts; and means responsive to relative movements between said flexible means and the other of said end parts for varying the relative amounts of fluid supply from said supplying means to said motors for urging said platen in a direction to counteract said relative movement.

13. In a press having a head, a bed, a platen reciprocable therebetween, a plurality of spaced fluid motors for actuating said platen, and fluid pressure supply means for supplying actuating

fluid to said motors; means for maintaining said platen parallel to a predetermined reference plane throughout its reciprocating movements and comprising flexible inextensible means extending from each side of said head to the opposite sides of said bed and passing transversely across said platen; journal means at opposite sides of said platen for supporting said flexible means; means rigidly anchoring said flexible means at each side of said bed; journal means at each side of said head, said flexible means passing thereover and across said head and being interconnected; spring means urging said flexible means into a predetermined position relative to said head and being sufficiently strong to maintain said platen level before it engages the work; and other means responsive to movements of said flexible means relative to said head for varying the relative quantities of fluid supply to said motor means for maintaining said platen level under load.

14. In a press with a head, a bed, a platen reciprocable therebetween, a plurality of spaced fluid motors for actuating said platen, and fluid pressure supply means for supplying fluid to said motors; means comprising flexible inextensible means connected between said head and bed, extending transversely across said platen, and operating as a parallel motion mechanism; said flexible means extending across said head and being connected and being anchored on said bed; and means responsive to relative movements between said flexible member and head brought about by tilting movements of said platen for varying the relative pressures at which fluid is supplied to said motors.

15. In a press having a head, a bed, a platen, a plurality of actuating motors for said platen, and fluid supply means for said motors; leveling means for said platen comprising flexible inextensible means extending from said head to said bed, passing transversely across said platen, and acting as a parallel motion mechanism; said flexible means extending across said head and being connected; adjustable anchor means rigidly securing said means to said bed; valve means connected between each of said motors and said fluid supply means and operable to control the pressure supplied to said motors; and means responsive to movements of said flexible means across said head as brought about by tilting movements of said platen for operating said valve means to vary the pressures acting on said motors.
